UNITED STATES PATENT OFFICE.

JOSEPH F. HEWITT, OF ALLEGHENY, PENNSYLVANIA.

DESIGN FOR A GRATE-FRONT.

SPECIFICATION forming part of Design No. 28,821, dated June 7, 1898.

Application filed November 11, 1896. Serial No. 611,762. Term of patent 7 years.

To all whom it may concern:

Be it known that I, JOSEPH F. HEWITT, a citizen of the United States, residing at Allegheny, in the county of Allegheny and State of Pennsylvania, have invented and produced 5 a new and original Design for Grate-Fronts, of which the following is a specification.

In the accompanying drawing, which makes part of this specification, the figure is a perspective of my design.

My design is for a grate-front which is used as a gas-burner.

2, the central portion of the burner, consists of an upright flat face. This is flanked on 15 each edge by the side pieces 3, 3, extending rearwardly from the same and making an oblique angle with the central portion 2.

Where the lines of the side pieces meet the central portion, I have a rope-like effect at 4, 4.

5 5 are the horizontal grooves running across 20 the front and provided, as usual, with perforations.

6 6 are parallel lines presenting a woolly or fluffy appearance between said grooves.

Having described my invention, I claim— 25

The design for grate-front substantially as herein shown and described.

In testimony whereof I have hereunto set my hand this 10th day of November, A. D. 1896.

JOSEPH F. HEWITT.
